WRENCH

John H. Thompson, Long Beach, Calif.

Application December 20, 1937, Serial No. 180,821

4 Claims. (Cl. 81—99)

This invention relates to a wrench which is adapted to a considerable variety of uses, being more particularly intended for turning cylindrical and annular objects.

5 An object of the invention is to provide a wrench of this kind which is particularly well adapted for being used in a great variety of situations many of which will involve reaching parts which it would be difficult to obtain access to and 10 to operate upon by most of the wrenches now on the market.

More specifically speaking, it is one of the objects of the invention to provide an improved handle means for a wrench of the kind to which 15 the invention pertains, said handle means having at each end a shape adapting it for attachment to the head of the wrench.

Another object of the invention is to provide a novel and advantageous combination of toothed 20 gripping heads or members which are pivoted together in such a manner that, in combination with the handle means above mentioned, a superior action of the wrench is obtained.

A still further object of the invention is to provide improved means to cause the teeth of the wrench to grip the object to be turned.

Other objects, advantages and features of the invention may hereinafter appear.

Referring to the accompanying drawing which 30 illustrates what is at present deemed to be a preferred embodiment of the invention,

Fig. 1 is a side elevation of the tool looking at the jaw members in an edgewise manner.

Fig. 2 is a view looking at right angles to the 35 showing of Fig. 1, the head of the tool being shown in plan as applied to a circular rod.

Fig. 3 is a plan view of a modified wrench head. Fig. 4 is a section on line 4—4 of Fig. 2.

Referring in detail to the drawing, in Figs. 1 40 and 2 the gripping portion of the jaw is shown as consisting of a main or mounting jaw 10 having through it a central opening 11 which is hexagonally or otherwise shaped in such a manner as to adapt it to receive a similarly shaped 45 portion of an operating handle 12, the handle shown having a short right angularly extending limb or arm 13 the end portion of which fits snugly within said opening.

Said jaw 10 is provided with external gripping 50 teeth which are arranged in two sets with respect to their inclination, there being at one side a set of teeth 14 and at the other side of said jaw a set of teeth 15. The jaw is provided also with a lug or short arm 17 which projects from

the side thereof opposite to its toothed portion, said lug 17 being located diametrically opposite to the meeting point of the two sets of teeth 14 and 15, the teeth in each of said sets being inclined toward the side of the jaw which is opposite to said lug. 5

An arcuate auxiliary jaw 20 is provided one end portion of which is furnished with bifurcations 21, said bifurcations receiving a pivot 22 whereby this portion of the arcuate jaw is pivotally connected with the main jaw 10. Said jaw 20 is furnished with an exterior set of teeth 23 and with an interior set of teeth 24, the exterior teeth having their points directed away from the pivoted portion of the jaw, and the interior teeth 15 being provided with points directed toward the pivoted portion thereof. The sets of teeth 23 and 24 combine to form a continuously toothed exterior for the toothed portion of said jaw 20.

The handle 12 shown in Figs. 1 and 2 has its 20 outer end shaped the same in cross section as its opposite end in order that either end portion of the handle may be fitted within the opening of the main jaw 10, in an axial relation to said jaw to turn it. Stop means 25 and 26 are shown 25 to limit the extent to which either end of the handle may be inserted within the wrench head 10, also a spring pressed ball 27 is shown to steady the operation of the inserted handle.

In Fig. 3 is shown a modification wherein the 30 parts are very similar to those which have been described and are therefore lettered the same with the addition of the letter "a". In this view the tool is shown applied interiorly to a pipe 30 which it is desired to turn. 35

By taking out the pivot pin 22a, removing the arcuate jaw and then replacing it in the reverse position, the teeth at the right (instead of at the left) of the center of the jaw 10a as viewed in Fig. 3, will be caused to engage the interior surface of the pipe 30 during a turning operation. 40 This feature of the invention adds to the wearing quality of the tool by doubling the number of teeth of the jaw 10a which can be used for internal pipe gripping. 45

In operation the wrench shown in Figs. 1 and 2, after the tool has been applied to the rod 24 or other object to be turned by being interiorly gripped between the jaws of the wrench, the tool is rotated as viewed in Fig. 2, in a left hand, 50 direction indicated by the arrow in said view, thereby applying the teeth 15 of the main jaw in one direction against a side of the bar and at the same time applying the internal teeth 24 of the auxiliary jaw in a reverse direction against the 55

opposite side of said bar. Owing to the arcuate shape of the auxiliary jaw its teeth will grip tighter and tighter upon the bar as the torsional movement advances.

5 A reverse action to that just described takes place in the structure shown in Fig. 3 when the wrench is applied interiorly to the pipe 30. In this case the external teeth 23a of the arcuate jaw bite into the inner surface of one side portion of the pipe 30 while the teeth 14a of the main jaw engage the opposite side of the inner surface of said pipe. The rotation of the tool in this case is in a right hand direction indicated by the arrow in said view, and the more torsional 10 force which is applied thereto the more firmly will the teeth of the auxiliary jaw bite into the inner surface of the pipe to be turned. The wrench shown in Fig. 2 may, of course, be applied in the manner just stated, though the teeth 15 20 10b of the jaw 10a are uniformly pitched and are arranged in a single continuous series.

A coiled leaf spring 31 is shown in both embodiments of the invention, said spring being contained in a runway made up of opposite 25 grooves 32 and 33 (Fig. 2) formed respectively in the main jaw and the arcuate jaw. Said runway is sufficiently enclosed to prevent the escape of said spring, but has a side opening between the base portion of the arcuate jaw and a shoulder 30 35 34 of the main jaw of sufficient width to allow a small instrument to be inserted to move said spring from end to end of said runway. Said spring exerts yielding pressure diametrically of its circular form, thus tending to swing the arcuate jaw inwardly when positioned as in Fig. 2, and to swing said arcuate jaw outwardly when the spring is adjusted to the opposite end of its runway, as shown in Fig. 3. Hence in Fig. 2 said spring is adjusted to cause the internal teeth 24 of the jaw 20 to grip externally an object to be turned, whereas in Fig. 3 the spring is shown adjusted to cause the external teeth of the arcuate jaw to act upon the interior of an annular object. The bottom of the groove 33 is shown as being substantially straight, but the bottom of the groove 32 is convexed, thus causing the runway for the spring 31 to be wider at its ends than in its center in order to cause said spring to remain in its adjusted positions. The stop shoulders 35 in the main jaw contract the ends of the runway for said spring and stop said spring at the desired points.

The spring member 31 (or 31a) need not be in the form of a coil, but a great variety of resilient bodies could be successfully used in this situation, and the claimed invention is not limited to the kind of spring shown.

Owing to the detachable character of the handle 12, when it is desired to reverse the direction of rotation of the toothed portion of the wrench, it is only necessary to withdraw the handle from one side of the opening provided therefor in the main wrench head and reinsert the handle into

the opposite side of said opening. Hence in operating the wrench it is unnecessary to provide any auxiliary means for connecting the toothed portion of the wrench with the handle portion thereof and a simpler construction results than 5 would be the case if this was necessary.

I claim:

1. A wrench of the type described having an exteriorly toothed main jaw of a generally circular character and furnished with a radial projection, an arcuate auxiliary jaw having one of its end portions pivotally connected with said projection, said arcuate jaw having both external and internal gripping teeth, means attachable to said main jaw to turn it about an axis parallel 10 to the axis of the swing of said auxiliary jaw, and a spring carried by the wrench, said spring being interposed between said jaws and being adjustable between two positions at opposite sides of said pivot connection in one of which it tends 15 to swing said auxiliary jaw in one direction and in the other of which it tends to swing said auxiliary jaw in the reverse direction.

2. A wrench having a main jaw furnished with circularly arranged external gripping teeth, an arcuate auxiliary jaw having gripping teeth on both its convex and its concave side, said auxiliary jaw being pivotally connected with said main jaw to swing in relation thereto, and a resilient body, there being grooves in adjacent portions 30 of said jaws which cooperate to form a runway wherein said resilient body is confined under compression, said body being interposed between said jaws and being adjustable along said runway between two positions at opposite sides of said 35 pivot and when in one of said positions in said runway tending to swing said auxiliary jaw towards said main jaw and when in the other of said positions tending to swing said auxiliary jaw away from said main jaw.

3. The subject matter of claim 2 and, said runway having widened end portions aiding to retain said resilient body in its aforesaid adjusted positions.

4. A wrench of the type described having an exteriorly toothed main jaw of a generally circular character and furnished with a radial projection, an arcuate jaw having one of its end portions pivotally connected in a removable, reversible manner with said projection, said arcuate jaw having gripping teeth on its convex portion, a handle means axially connectable with said main jaw to turn said jaw in relation to said arcuate jaw, the toothed portion of said main jaw occupying a sufficient portion of its periphery 55 to cooperate with the exterior teeth of said arcuate jaw for interior gripping of annular objects in both of its attached positions afforded by the aforesaid reversible attachment thereof, and resilient means mounted upon the wrench to urge 60 said arcuate jaw toward its gripping position for both internal and external gripping operations.

JOHN H. THOMPSON.
